ELEVATOR SAFETY DEVICE

Patrick Paquin, Timmins, Ontario, Canada

Application January 13, 1947, Serial No. 721,818

6 Claims. (Cl. 187—90)

1

The present invention pertains to a novel elevator safety device having the purposes disclosed in my co-pending application Serial No. 609,225 filed August 6, 1945, now abandoned, and consisting of various improvements and modifications thereof.

The principal object of this invention, as in the earlier invention, is to provide simple and effective means of arresting the descent of a falling elevator due to a broken cable or other cause. This object is accomplished generally by the use of a speed-actuated mechanism which throws gripping members or dogs into engagement with the rails, thereby bringing the elevator to a stop shortly after the uncontrolled descent has started.

In the accomplishment of this object, the elevator carries a rotatable shaft on which is mounted a wheel that rides in engagement with one of the rails. The shaft carries a loose clutch member and a complementary slidable clutch element operated by a centrifugal governor. When the speed of the elevator becomes excessive, the governor throws the clutch element into engagement with the clutch member, and the latter operates the holding dogs. A one-way drive is provided between the wheel and the shaft so that the latter rotates only on the descending movement of the elevator.

The binding dogs are carried by shafts also journaled in bearings on the elevator. Levers extending laterally of these shafts carry a pair of nuts in which is mounted a reversely threaded screw. The aforementioned clutch member carries a sprocket wheel connected by means of a chain to another sprocket wheel on the screw. Thus, when the clutch is engaged, the screw is driven and the nuts are displaced on the screw. The latter movement turns the dog-carrying shafts by means of the levers, and the dogs are thus brought into binding engagement with the rails.

The invention is fully disclosed by way of example in the following description and in the accompanying drawings in which:

Figure 1 is a bottom plan view of the mechanism, showing the elevator guide rails in section;

Figure 2 is a vertical elevation;

Figure 3 is a section on the line 3—3 of Figure 1; and

Figure 4 is a section on the line 4—4 of Figure 1.

Reference to these views will now be made by use of like characters which are employed to designate corresponding parts throughout.

The elevator 1 shown in Figure 1 moves between a pair of vertical guide rails 2. The safety mechanism is carried by the elevator and includes a shaft 3 on which is slidably keyed a

2

governor sleeve 4. The shaft also carries a fixed disk 5 and a slidable clutch element 6. The latter is connected to the sleeve 4 by rods 7 passing through the disk 5. A disk 8 is formed on the sleeve 4 and is joined to the disk 5 by a number of flat springs 9 carrying weights 10. A coil spring 11 surrounds a portion of the shaft 2, having one end bearing against an enlarged end 12 of the sleeve 4 and the other end engaged by a pair of adjustable nuts 13 on the shaft, whereby to hold the clutch element 6 in a retracted position.

On the shaft is also mounted a loose wheel or tire 14 riding along one of the rails 2. The member 14 carries a series of pawls 15 adapted to engage and drive a ratchet 16 fixed on the shaft 3, as the elevator descends. In the ascending direction, the pawls merely ride over the ratchet 16, and the mechanism associated with the shaft 3 is then inoperative.

The shaft 3 carries another loose sleeve 17 formed with a complementary clutch element 18 opposite the member 6 and normally spaced therefrom.

Suitable bearings 19 carried by the elevator support a pair of shafts 20 lying transversely on the shaft 3. Each shaft 20 is interrupted at 21 and carries, at the break, a pair of outwardly extending levers 22 between which is supported a nut 23. A reversely threaded screw 24 is passed through the two nuts and carries a sprocket wheel 25. Another wheel 26 is mounted on the sleeve 17 in line with the wheel 25, and the two wheels are joined by a sprocket chain 27. The shaft 3 may be held in a bearing 28 as shown in Figure 2.

The shafts 20 carry dogs 29 adapted to bind against the sides of the rails 2 under the conditions presently to be described. Each dog has a handle or lever 30 by means of which it may be taken out of engagement with the rail. The two shafts 20 are preferably geared together at 31 for simultaneous operation.

In the operation of the device, the descending elevator rotates the shaft 3 and the governor sleeve 4. In case of excessive speed, as when a cable breaks, the speed of the sleeve 4 is greatly increased, and the weights 10 are thus thrown outward with sufficient force to cause the sleeve 4 to slide against the pressure of the coil spring 11. The clutch member 6 is thereby brought into engagement with the clutch member 18, driving the sprocket 26, the chain 27 and the sprocket 25 which in turn rotates the screw 24.

The rotation of the reversely threaded screw 24 draws the nuts 23 inward, causing the levers 22 to turn the shafts 20. The ends of the links attached to the nuts swing in an arc, and the vertical component of the arc is taken up by a lifting movement of the screw 24, so that no other

means need be provided to permit play in the connections between the several parts.

The turning of the shaft 24 and shafts 20 in the manner described brings the dogs 29 into binding engagement with the sides of the rails 2, whereby the uncontrolled descent of the elevator is arrested. When the elevator has been emptied of its load and the damage is to be repaired, the dogs are released from the rails by hammering on the levers 30. The geared connection 31 between the shafts 20 causes the dogs to act in unison.

Although a specific embodiment of the invention has been illustrated and described, it will be understood that various alterations in the details of construction may be made without departing from the scope of the invention as indicated by the appended claims.

What I claim as my invention is:

1. In an elevator safety device, an elevator moving between guide rails, a rotatable shaft carried by said elevator, a rail-engaging wheel mounted thereon, a loose clutch member on said shaft, a centrifugal governor on said shaft, a complementary clutch element operable by said governor to engage said clutch member, a pair of shafts transverse of the first shaft and journaled on said elevator, levers extending outwardly from said pair of shafts, nuts carried by said levers, a reversely threaded screw mounted in said nuts, a driving connection from said clutch member to said screw, and dogs mounted on said pair of shafts and adapted to bind on said rails.

2. In an elevator safety device, an elevator moving between guide rails, a rotatable shaft carried by said elevator, a rail-engaging wheel mounted thereon, a loose clutch member on said shaft, a centrifugal governor on said shaft, a complementary clutch element operable by said governor to engage said clutch member, a pair of shafts transverse of the first shaft and journaled on said elevator, levers extending outwardly from said pair of shafts, nuts carried by said levers, a reversely threaded screw mounted in said nuts, a driving connection from said clutch member to said screw, and dogs mounted on said pair of shafts and adapted to bind on said rails, the shafts of said pair being geared together.

3. In an elevator safety device, an elevator moving between guide rails, a rotatable shaft carried by said elevator, a rail-engaging wheel mounted thereon, a loose clutch member on said shaft, a centrifugal governor on said shaft, a complementary clutch element operable by said governor to engage said clutch member, a pair of shafts transverse of the first shaft and journaled on said elevator, levers extending outwardly from said pair of shafts, nuts carried by said levers, a reversely threaded screw mounted in said nuts, a driving connection from said clutch member to said screw, and dogs mounted on said pair of shafts and adapted to bind on said rails.

5 4. In an elevator safety device, an elevator moving between guide rails, a rotatable shaft carried by said elevator, a rail-engaging wheel mounted thereon, a loose clutch member on said shaft, a centrifugal governor on said shaft, a complementary clutch element operable by said governor to engage said clutch member, a pair of shafts transverse of the first shaft and journaled on said elevator, levers extending outwardly from said pair of shafts, nuts carried by said levers, a reversely threaded screw mounted in said nuts, a driving connection from said clutch member to said screw, and dogs mounted on said pair of shafts and adapted to bind on said rails.

10 5. In an elevator safety device, an elevator moving between guide rails, a rotatable shaft carried by said elevator, a rail-engaging wheel mounted thereon, a loose clutch member on said shaft, a centrifugal governor on said shaft, a complementary clutch element operable by said governor to engage said clutch member, a pair of shafts transverse of the first shaft and journaled on said elevator, levers extending outwardly from said pair of shafts, nuts carried by said levers, a reversely threaded screw mounted in said nuts, said nuts constituting the sole support for said screw, a driving connection from said clutch member to said screw, and dogs mounted on said pair of shafts and adapted to bind on said rails.

15 6. In an elevator safety device, an elevator moving between guide rails, a rotatable shaft carried by said elevator, a rail-engaging wheel mounted thereon, a loose clutch member on said shaft, a centrifugal governor on said shaft, a complementary clutch element operable by said governor to engage said clutch member, a pair of shafts transverse of the first shaft and journaled on said elevator, levers extending outwardly from said pair of shafts, nuts carried by said levers, a reversely threaded screw mounted in said nuts, said nuts constituting the sole support for said screw, a driving connection from said clutch member to said screw, and dogs mounted on said pair of shafts and adapted to bind on said rails.

20 7. In an elevator safety device, an elevator moving between guide rails, a rotatable shaft carried by said elevator, a rail-engaging wheel mounted thereon, a one-way drive between said wheel and shaft and operable in the descending direction of the elevator, a loose clutch member on said shaft, a centrifugal governor on said shaft, a complementary clutch element operable by said governor to engage said clutch member, a pair of shafts transverse of the first shaft and journaled on said elevator, levers extending outwardly from said pair of shafts, nuts carried by said levers, a reversely threaded screw mounted in said nuts, a driving connection from said clutch member to said screw, and dogs mounted on said pair of shafts and adapted to bind on said rails.
